CLAIM

I claim the ornamental design for a pusher and measuring cup, as shown and described.

DESCRIPTION

FIG. 1 is a front perspective view of one embodiment of a pusher/measuring cup of the present disclosure;

FIG. 2 is a rear perspective view of the pusher/measuring cup of FIG. 1;

FIG. 3 is a front elevational view of the pusher/measuring cup of FIG. 1;

FIG. 4 is a rear elevational view of the pusher/measuring cup of FIG. 1;

FIG. 5 is a first side elevational view of the pusher/measuring cup of FIG. 1;

FIG. 6 is a second side elevational view of the pusher/measuring cup of FIG. 1;

FIG. 7 is a top plan view of the pusher/measuring cup of FIG. 1; and,

FIG. 8 is a bottom plan view of the pusher/measuring cup of FIG. 1.

The broken lines illustrated show portions of the measuring cup that form no part of the claimed design.
